(57) **CLAIM**

The ornamental design for bottle, as shown and described.

DESCRIPTION

FIG. 1 is a top, front, right side perspective view of the bottle in accordance with our new design;

FIG. 2 is a top plan view thereof;

FIG. 3 is a bottom plan view thereof; and,

FIG. 4 is a front elevational view thereof, the rear elevational view, right side elevational view, and left side elevational view being identical.

The broken lines shown in the drawing views are included for the purpose of showing environmental structure that forms no part of the claimed design.
